(57) **CLAIM**

The ornamental design for a combined fan with light fixture, as shown and described.

DESCRIPTION

FIG. 1 is a perspective view of a combined fan with light fixture;

FIG. 2 is a front view of the combined fan with light fixture;
FIG. 3 is a rear view of the combined fan with light fixture;
FIG. 4 is a right side view of the combined fan with light fixture;

FIG. 5 is a left side view of the combined fan with light fixture;

FIG. 6 is a bottom view of the combined fan with light fixture;

FIG. 7 is a top view of the combined fan with light fixture; and,

FIG. 8 is a perspective view of the combined fan with light fixture installed on a ceiling of a structure.

The broken lines illustrate portions of the combined fan with light fixture and environmental structure that form no part of the claimed design.
